UNITED STATES PATENT OFFICE.

ROBERT A. ANDERSON, OF MONTCLAIR, NEW JERSEY, ASSIGNOR TO GAMON METER COMPANY, OF NEWARK, NEW JERSEY, A CORPORATION OF NEW JERSEY.

GEAR TRAIN FOR WATER METERS.

Application filed March 11, 1927. Serial No. 174,606.

This invention relates to water meter gear trains and particularly to shafts and spin-dles as used in submerged conditions or at least subject to moisture whereby wheels and 5 the like, mounted for rotation on the shafts, may be caused to adhere, due to the impurities and chemical action of the water on the shafts.

While such shafts are usually made of a 10 phosphor bronze alloy, it is found in practice that fine particles, entrained in the water, which may be considered as impurities, or such as may be caused by corrosion from chemicals in solution, can and do find 15 their way between the rotative wheels and body of a bare shaft, causing the same to stick and fail to function properly, destroying the perfection of operation of the wheels and hence rendering the meter unreliable.

20 This is more particularly noticeable in counting or accumulative registering trains in which the units wheel is frequently moved while the next adjacent wheel, moved by a carrying gear, is rotated at one tenth 25 the number of revolutions, and the remaining wheels in like reduced proportion, the last, in a train of five, moving from one numeral space to another but once during the time the first wheel has revolved ten 30 thousand times.

Such sluggish and irregular movement of the less frequently operated wheels, and also the corresponding carrying gears, is 35 highly conducive to a condition called "freezing", that is adhesion to the shaft, aggravated by impurities in the water.

The main object of the invention is therefore to provide a casing or sleeve permanently fixed at the shaft, such sleeve being 40 of an impervious nature, presenting a hard unyielding body, acting as a lubricant or insulator for the parts rotatable thereon and while fixed on the shaft, will not "freeze" or cohere to the bores of such parts.

45 This important object is attained by the novel construction and combination of parts hereinafter described and illustrated in the accompanying drawing, forming a material part of this disclosure, and in which:

50 Figure 1 is a top plan view of a conventional water meter showing the counting wheels and carrying gears as mounted on shafts made in accordance with the invention.

Figure 2 is a front elevational view of the 55 same.

Figure 3 is an end view thereof, one of the gear train supports being omitted.

Figure 4 is a fragmentary longitudinal 60 sectional view of an end wheel unit as mounted on its shaft, drawn to an enlarged scale.

Figure 5 is a similar view of a portion of the carrying gear and its mount as used in 65 the train.

The registering device shown consists of a frame composed of two metallic discs 10 and 11, respectively front and rear, the front disc having a substantially central, elongated rectangular aperture 12.

70 These discs are rigidly connected together in spaced relation by plate brackets 13 disposed adjacently outward beyond the ends of the aperture 12.

A spindle 14 is journaled in the discs, 75 centrally below the aperture to extend outwardly at the rear, this spindle being connected in the usual manner with the driving mechanism of the meter (not shown).

Fixed on the spindle, adjacent the rear 80 disc 11, is a spur gear 15, in mesh with a pinion 16 secured on another spindle 17 mounted at its ends in the respective discs and also carrying a worm 18 adapted to transmit motion to a spur gear 19 located on 85 a shaft 20 having reduced ends 21 journaled in the brackets 13.

The gear 19 constitutes part of the first or unit registering element of the train wheels and is revoluble with a spacer 22 90 having an annular flange 23 juxtaposed with a counting wheel 24 bearing numerals from 0 to 9 and having fixed on its opposite side a disc 25 in the periphery of which is formed two teeth.

The spacer 22 is reduced at its ends to act as a sleeve on which the counting wheel 24 and disc 25 are fixed in addition to the gear 19, to rotate freely, as a unit, on the shaft 20, each of the remaining units being 100 similarly independently mounted.

Adjacent the disc 25 is a spur gear mounted alongside another counting wheel, at the opposite side of which is another disc having a pair of teeth, the gear, wheel and disc being fixed on a sleeve revoluble on the shaft, as can best be seen in Figure 4, where a gear 28, wheel 29 and spacer 30 are fixed 105

on a sleeve 31, in this case having a flange 32 in place of a disc, it being the end unit.

Another shaft 33, having its reduced ends 34 fixedly mounted in the brackets 13, parallel to the shaft 20, has revolvably mounted upon it a series of mutilated carrying pinions 35 arranged to engage the gears in each unit to advance the wheels one tenth of a revolution, the carrying pinions being cut away 10 at intervals, the remaining portions riding on the peripheries of the discs 25 and engaging the teeth therein whereby the gear in the next unit is rotated such proportion of a revolution as to disclose the next higher 15 numeral on the counting wheel forming part of that unit, the wheels being seen through the aperture 12 in the front plate.

The foregoing is generally descriptive of well known counting registers for meters etc., 20 and is not new, the invention residing in the improved shafts 20 and 33, which may be made of any metal, phosphor bronze being preferred because of its immunity from corrosion as compared with other common 25 metals that might be used for the purpose.

Extending around the shafts 20 and 33 are sheaths 20' and 33' composed of molded graphite, hard rubber, porcelain or other rigid impervious material, shrunk, vulcanized or otherwise permanently fixed to become substantially a unit, these sheaths hav-

ing a wall of uniform thickness so that their outer exposed surface is concentric with the axis of the shafts.

The length of the sheaths may vary from 35 that of the shafts to conform with requirements and it is also possible to form the sheaths in short sections if preferred.

While certain preferred embodiments of this device have been shown and described, it 40 will be understood that changes in the form, arrangements, proportions, sizes and details thereof may be made without departing from the scope of the invention as defined in the appended claims. 45

Having thus described my invention, what I claim as new and desire to secure by Letters Patent, is:—

1. Phosphor bronze shafts as used in water meters, and sheaths of non-corrodible material secured on said shafts to form a unit therewith, said sheaths acting as journals for members mounted thereon. 50

2. Phosphor bronze shafts as used in water meters, and uniformly thick bearing sleeves of non-metallic substance fixed permanently on said shafts, said sheaths acting as journals for members mounted thereon. 55

This specification signed and witnessed this seventh day of March, 1927.

ROBERT A. ANDERSON.
